UNITED STATES PATENT OFFICE.

RADE N. PEROVICH, OF WASHOE, MONTANA.

DESIGN FOR A RAILROAD-SPIKE.

52,773.

Specification for Design.

Patented Dec. 17, 1918.

Application filed April 18, 1917. Serial No. 163,085. Term of patent 7 years.

To all whom it may concern:

Be it known that I, RADE N. PEROVICH, citizen of the United States of America, residing at Washoe, in the county of Carbon and State of Montana, have invented a certain new, original, and ornamental Design for Railroad-Spikes, of which the following is a specification, reference being had therein to the accompanying drawing, wherein—

Figure 1 is a front elevation of a railroad spike.

Fig. 2 is a side elevation of the railroad spike.

Fig. 3 is a rear elevation of the railroad spike.

Fig. 4 is a bottom plan view of the railroad spike.

Fig. 5 is a top plan view of the railroad spike.

I claim:

The ornamental design for a railroad spike, as shown.

In testimony whereof I hereunto affix my signature.

RADE N. PEROVICH.
